US0D1095337S

(12) **United States Design Patent** (10) **Patent No.:** **US D1,095,337 S**
(45) **Date of Patent:** **** Sep. 30, 2025**

(54) **ELECTRIC MOTORCYCLE**

(71) Applicants: **Shenzhen Chitado Technology CO., LTD**, Shenzhen (CN); **3COLOR INDUSTRY & TRADING CO., LTD**, Jinhua (CN)

(72) Inventors: **Dianxuan Zhang**, Shenzhen (CN); **Lusheng Li**, Jinhua (CN)

(73) Assignees: **Shenzhen Chitado Technology CO., LTD**, Shenzhen (CN); **3COLOR INDUSTRY & TRADING CO., LTD**, Jinhua (CN)

(**) Term: **15 Years**

(21) Appl. No.: **29/922,800**

(22) Filed: **Dec. 26, 2023**

(30) **Foreign Application Priority Data**

Sep. 28, 2023 (CN) 202330639158.3

(57) **CLAIM**

The ornamental design for an electric motorcycle, as shown and described.

DESCRIPTION

FIG. 1 is a top, rear and left side perspective view of an electric motorcycle showing our new design;

FIG. 2 is a top, front and left side perspective view thereof;

FIG. 3 is a left side elevation view thereof;

FIG. 4 is a right side elevation view thereof;

FIG. 5 is a front elevation view thereof;

FIG. 6 is a rear elevation view thereof;

FIG. 7 is a top plan view thereof; and,

FIG. 8 is a bottom plan view thereof.

The broken line in the drawing depict portions of the electric motorcycle that form no part of the claimed design.

1 Claim, 8 Drawing Sheets
